UNITED STATES PATENT OFFICE.

OTHO M. OTTE, OF TARENTUM, PENNSYLVANIA, ASSIGNOR, BY DIRECT AND MESNE ASSIGNMENTS, TO RAYDEX MANUFACTURING COMPANY, OF BRACKENRIDGE-PENNSYLVANIA, A CORPORATION OF PENNSYLVANIA.

BUTTON-ARRANGING CLOTHES WRINGER.

Application filed January 30, 1922. Serial No. 532,759.

To all whom it may concern:

Be it known that I, OTHO M. OTTE, a citizen of the United States, and a resident of Tarentum, in the county of Allegheny and the State of Pennsylvania, have made a new and useful Invention in Button-Arranging Clothes Wringers, of which the following is a specification.

This invention relates to clothes wringers. The buttons on clothes when run through wringers as ordinarily constructed are liable to be either torn from the clothes or broken by the compression rolls of the wringer, owing to the fact that a large proportion of them enter between the compression rolls at an improper angle with relation to the line of travel of the clothes through the rolls. I have found that if the buttons are laid flat before entering the rolls, the tendency to tear them from the clothes or to break them is reduced to a minimum and an object of this invention is to provide a wringer in the operation of which, the buttons on clothes prior to their entrance between the wringer rolls are automatically adjusted and arranged so as to enter the rolls in a position to minimize the crushing of the buttons or the tearing of them from the clothes.

A further object of this invention is to provide a wringer combining in its make-up a button adjuster and safety guard, whereby the hands of the operator will be prevented from passing into the compression rolls.

These, as well as other objects which will readily appear to those skilled in this particular art, I attain by means of the device described in the specification and illustrated in the drawings accompanying and forming part of this application.

In the drawings, Figure 1 is a side sectional view in elevation of a portion of a clothes wringer embodying this invention and Figure 2 is a similar view of a modification of said wringer.

In constructing a wringer embodying this invention, the ordinary frame consisting of the end posts slotted to receive the bearing blocks for journaling compression rolls may be utilized. The compression rolls may be geared together as is now common, but in constructing a wringer in accordance with

this invention, compression rolls 3 and 4 are so mounted in their bearing blocks 5 and 7 55 that the axes of the rolls are vertically offset as shown in Figs. 1 and 2.

In a one way wringer, each of the wringer end posts 8 carries a forwardly projecting bracket 9 and substantially in line with the lower compression roll 4, an idler roller 10 has its reduced ends or trunnions 11 journaled.

A soft rubber belt 12 of substantially the same width as the compression rolls extends 65 around lower compression roll 4 and idler roller 10.

Each of the brackets 9 above the upper run of belt 12 is provided with a bearing slot 13 and within this slot the reduced ends 70 or trunnions 14 of an idler roller 15 are journaled. A soft endless rubber belt 16 passes around compression roll 3 and idler roller 15. The inclination of walls 17 of slots 13 is such that the outer end (that farthest removed from compression roll 3) of belt 16 may be more or less freely moved 75 away from belt 12 to present an opening between the lower run of belt 16 and the upper run of belt 12 for the entrance of clothes or 80 other material to be wrung between the compression rolls.

The vertical offsetting of the axes of the compression rolls materially increases the compression area between the belts over 85 what it would be if the axes of the rolls were in the same vertical plane, thereby materially increasing the effectiveness of the device as a wringer.

In Fig. 2, the device illustrated is a two 90 way or double wringer which is capable of being run in both directions and is adapted to take the place of the ordinary power wringer as now used in connection with washing machines.

The clothes or other material to be wrung may be entered from either side depending upon the direction of rotation of the compression rolls.

Having thus described my invention, what 100 I claim is:—

In a wringer, upper and lower compression rolls having their axes vertically offset, an idler roller in front of said lower compression roll, an endless belt passing around 105 said lower roll and roller, an idler roller in

front of said upper compression roll and positioned over an unsupported section of said lower belt, an endless belt passing around said upper roll and roller and a bracket having a slot for yieldingly supporting said upper roller in vertically offset relation to said lower roller whereby mate-

rial is initially compacted between said yieldingly mounted upper roller and an unsupported section of said lower belt.

In testimony whereof, I have hereunto subscribed my name this day of Jan. 25, 1922.

OTHO M. OTTE.
